Primary Examiner — Paula Greene(74) *Attorney, Agent, or Firm* — Shams, Rodriguez & Mozwecz, P.C.(57) **CLAIM**

The ornamental design for a handle grip, as shown and described.

DESCRIPTION

FIG. 1 is a side view of a handle grip, showing my new design; and,

FIG. 2 is a perspective view of a handle grip thereof. The broken line showing the extended handle rod in FIG. 2 forms no part of the claimed design.
